UNITED STATES PATENT OFFICE.

GEORGE HAZELTON, OF PORTADOWN, IRELAND, ASSIGNOR TO THE BRITISH METAL AND TOY MANUFACTURERS LIMITED, OF LONDON, ENGLAND.

MECHANICAL TOY.

1,376,766.

Specification of Letters Patent.

Patented May 3, 1921.

Application filed October 14, 1920. Serial No. 416,926.

To all whom it may concern:

Be it known that I, GEORGE HAZELTON, a subject of the King of Great Britain and Ireland, residing at 68 Woodhouse street, 5 Portadown, county Armagh, Ireland, have invented a new and useful Mechanical Toy, of which the following is a specification.

This invention relates to toy cranes and like toy apparatus and the object of the 10 invention is to provide a construction in which the movement of a weight serves to store energy in a part of the toy and to rotate the jib, which energy, when the weight has been moved to the required position and 15 disconnected, causes the return of the parts of the toy to the initial position.

According to this invention the toy crane or the like consists essentially in the combination of a suitable base or support, a 20 jib or like projecting part rotatably mounted with respect to the base, a cord or other flexible suspension member passing over the head of the jib and taken to a winding drum fixed with respect to the base or support and 25 a spring so arranged between the jib or the like and the base or support, that the lowering of a weight when connected to the free end of the suspension member, charges the spring and revolves the jib in one direction 30 freely about the base, while disconnection of the weight from the suspension member after the weight has fallen through the desired distance, allows the charged spring to 35 return the moving parts of the crane to their initial positions.

The invention is illustrated in the accompanying drawing in which Figure 1 is a side elevation partly in section and Fig. 2 is a plan view of a toy crane. 40 *a* is the base of the crane to which is fixed a vertical shaft *b*, carrying at its upper end a drum *c*. The shaft *b* and drum *c* do not rotate. Mounted upon the base *a* is the housing *d* which has suitable apertures to 45 allow it to rotate around the fixed shaft *b*. The housing contains on one side thereof a counter balance weight *d*¹ and to the other side is fixed the jib *e*. A stay *e*¹ connects the jib *e* to the housing *d* and this stay is bent 50 down inside the housing and is formed with a projection *e*². A light coiled spring *f* surrounding the shaft *b* is fixed at one end to the projection *e*² and at its other end to the shaft *b*. In the drawing it is shown passing 55 into an aperture *b*¹ in the shaft *b*.

The jib *e* is provided with suitable guides

such as the pulleys *e*³ *e*⁴. To the drum *c* is fixed one end of the cord *g*. This cord is coiled several times around the drum *c* and is then passed under the pulley *e*³ and over 60 the pulley *e*⁴.

As shown in the drawings the cord *g* is connected to a self releasing hook *h* which is pivotally suspended by the link *h*¹ and has a laterally projecting weight *h*². A weight 65 in the form of a bucket *i* is suspended by the hook *h* and puts the cord *g* in tension. As the cord *g* is pulling always tangentially from the periphery of the drum *c* and laterally with respect to the shaft *b* around 70 which the jib *e* rotates the effect is that the jib *e* and housing *d* rotate upon the shaft *b*, the cord *g* is unwound from the fixed drum *c* and the outer end of the cord *g* lowers the weight *i*. The rotation of the housing *d* 75 charges the spring *f* by winding it more tightly around the shaft *b*.

When the weight *i* reaches the surface upon which the base is standing, the weight *h*² rocks the hook on the link *h*¹ and the hook 80 is released. The spring *f* then unwinds and rotates the housing *d* and jib *e* in the opposite direction to that in which they were moved by the action of the weight *i*. During this reverse rotation the cord *g* or other 85 flexible connection is again wound around the drum *c*.

What I claim as my invention is:—

1. A mechanical toy having in combination a base, a vertical rod fixed with relation to the base, a drum concentric with the said rod and fixed with relation to said base, a housing rotatably mounted on said rod, a lateral projection carried by said housing, guides carried by the said projection, a coiled spring fastened at one end to the said rod and at the other end to the housing and a flexible suspension member fastened at one end to said drum, wound around the drum, passing through the guides 95 on the lateral projection and adapted to carry a weight.

2. A mechanical toy having in combination, a base, a vertical rod fixed with relation to the base, a drum fixed on said rod, a 105 housing rotatably mounted on said rod, a lateral projection carried by said housing, guides carried by the said projection, a coiled spring fastened at one end to the said rod and at the other end to the housing 110 and a flexible suspension member fastened at one end to said drum, wound around the

drum, passing through the guides on the lateral projection and adapted to carry a weight.

3. A mechanical toy having in combination a base, a vertical rod fixed with relation to the base, a drum concentric with the said rod and fixed with relation to said base, a housing rotatably mounted on said rod, a lateral projection carried by said housing, 10 guides carried by the said projection, a coiled spring fastened at one end to the said rod and at the other end to the housing, a flexible suspension member fastened at one end to said drum, wound around the drum, 15 passing through the guides on the lateral projection, a hook carried by the flexible suspension member, a weight carried by said hook, and a weight forming part of said hook to rock this latter and detach it 20 from the first mentioned weight when the descent of this latter is arrested.

4. A mechanical toy having in combination a base, a vertical rod fixed with relation to the base, a drum concentric with said rod and fixed with relation to the base, 25 a housing rotatably mounted on said rod, a lateral projection carried by said housing, pulleys carried by said projection, a coiled spring fastened at one end to the said rod and at the other end to the housing, a flexible suspension member fastened at one end to said drum, wound around said drum and guided by the pulleys on the said lateral projection and means attached to the flexible suspension member for carrying a 30 weight.

In witness whereof I have hereunto set my hand in presence of two witnesses.

GEORGE HAZELTON.
